UNITED STATES PATENT OFFICE

100,466

DESIGN FOR A COMBINATION CASE BEARER BELT BUCKLE OR SIMILAR ARTICLE

Helen Hughes Dulany, Chicago, Ill.

Application November 2, 1935, Serial No. 59,338

Term of patent 7 years

To all whom it may concern:

Be it known that I, Helen Hughes Dulany, a citizen of the United States of America, residing at Chicago, in the county of Cook and State of Illinois, have invented a new, original, and ornamental Design for a Combination Case Bearer Belt Buckle or Similar Article, of which the following is a specification, reference being had to the accompanying drawing, forming a part thereof, and in which

Fig. 1 is a view in perspective of a combination case bearer belt buckle embodying the design;

Fig. 2 is a front elevational view thereof; and

Fig. 3 is a top plan view.

The several parts of the case bearer belt buckle, which includes case bearer portions for cigarettes or the like provided with ornamental corrugations, and flat faced portions for receiving matches, because of being hinged together adapt themselves, in use, to the body of the wearer and thus provide a pleasing appearance in use.

I claim:—

The ornamental design for a combination case bearer belt buckle or similar article substantially as shown and described.

HELEN HUGHES DULANY.
